TOY ANIMAL

Edmund W. Baggott, Brooklyn, N. Y., assignor to
Ideal Novelty & Toy Co., Hollis, N. Y., a cor-
poration of New York

Application October 6, 1947, Serial No. 778,083

3 Claims. (Cl. 46—105)

1

This invention relates to a toy animal.

It is an object of the invention to provide a hollow toy body simulating an animal, such as a crocodile or the like, having a pair of axles disposed within the body and carrying wheels protruding therefrom to rest against the supporting surface along which the toy body may be drawn, and having legs mounted at the extremities of a supporting member pivoted centrally of the toy body adjacent each wheel axle, each wheel axle having a pair of oppositely disposed eccentric or cam elements which bear alternately against opposite sides of the pivoted leg supporting members or projections thereof to produce oscillating movement of the legs as the toy body is drawn along a supporting surface in simulation of the natural motion of the animal simulated.

A further object of the invention is the provision of a toy body of the character indicated having a movable lower jaw carrying an extension or arm pivoted within the toy body and having its inner free end disposed for engagement against one of the cam elements of the forward wheel axle for opening and closing the pivoted lower jaw simultaneously with the motion of the legs of the toy body, said extension or lever preferably being counterweighted at its inner free end to facilitate the closing action of the lower jaw and to lower said extension or lever for subsequent engagement against said respective double-duty cam element in order to produce alternate opening and closing action of the lower jaw.

Another object of the invention is the provision of a toy animal of the character indicated having a movable, preferably segmented tail portion to which motion may be imparted simultaneously with the movement of the legs of the toy animal as the animal is drawn or pulled along a supporting surface to simulate the "play" or swishing action of the tail of the animal simulated. This object is achieved by providing a lever or extension on the pivoted, rear leg-supporting member of the toy animal, which lever or extension extends rearwardly for alternately thrusting against opposite sides of the movable tail portion as said leg-supporting member is actuated by the respective cam elements of the rear wheel axle.

The foregoing objects as well as additional objects and advantages of the invention will be readily understood in the course of the following detailed description taken in connection with the accompanying drawings which illustrate a preferred embodiment of the invention, and wherein:

Fig. 1 is a plan view of a toy body incorporating

the features of the invention and simulating a crocodile, the top portion of the body being removed to show internal arrangement of parts, and the tail portion being shown in section, the view being taken substantially along line 1—1 of Fig. 2;

Fig. 2 is a side elevational view of the assembled toy body;

Fig. 3 is a bottom plan view of the assembled toy body;

Fig. 4 is a vertical longitudinal view of the assembled toy body taken substantially along line 4—4 of Fig. 1.

The toy body and the components thereof are preferably molded from any suitable synthetic plastic material and the body may be formed to simulate any desired animal, although the drawings illustrate the toy body formed in simulation of a crocodile.

The toy body is hollow and comprises a base portion 10 and an upper portion 11 which may be secured to base portion 10 adhesively or in any other desired manner. The upper portion 11 is shaped and dimensioned to extend forwardly of said base portion 10 to define a head and fixed upper jaw as indicated at 12.

Rotatably mounted in base portion 10 is a forward axle 13 carrying a pair of wheels 14 and a rear axle 22 carrying a pair of wheels 23. A supporting member 17 is centrally pivoted to an integral boss 18 of base portion 10 which is disposed forwardly of axle 13 as by means of a pivot pin 19, as clearly shown in Fig. 4, and said supporting member 17 is formed with a pair of legs 20 protruding laterally from the toy body on each side thereof. Supporting member 17 is further provided with a pair of longitudinal projections 17a extending rearwardly toward axle 13 for alternate engagement by cam elements 21 and 21a formed on said axle.

Cam elements 21 and 21a are preferably molded integrally with axle 13 and are disposed at opposite ends of said axle 13 in order to alternately engage against lateral projections 17a as wheels 14 and axle 13 rotate when the toy body is drawn along a supporting surface thereby producing reciprocating movement of legs 20 in simulation of the natural motion of the animal simulated. Cam element 21a is of greater axial length than cam element 21, preferably extending a slight distance beyond the medial longitudinal axis of the toy body, as best shown in Figs. 1 and 3, for a purpose to be hereinafter described. It will be noted that wheel opening 16a extends continuously across the bottom of base portion 10 to provide clearance for cam elements 21 and 21a

as axle 13 rotates, the opening 16a being shown substantially I-shaped in Fig. 3.

The rear axle 22 carries a pair of wheels 23 and cam elements 24 disposed at opposite ends of said rear axle in openings 23d. An oscillatory leg-supporting member 25 is centrally pivoted to an integral boss 26 of base 10 disposed rearwardly of axle 22 as by means of a pivot pin 27 and said supporting member 25 is formed with a pair of rear legs 28 protruding laterally from the toy body on each side thereof. Supporting member 25 is further provided with a pair of longitudinal projections 25a extending forwardly toward rear axle 22 for alternate engagement by cam elements 24 to produce reciprocating movement of rear legs 28 as the toy body is drawn along a supporting surface in a manner similar to that initially described for front legs 20. Supporting member 25 may be further provided with a medial rearward extension 25b for a purpose to be hereinafter indicated. As seen in Fig. 3, a T-shaped opening 23a is formed on each side of base portion 10 for the protrusion of each wheel 23 and to provide clearance for each cam element 24 as rear axle 22 rotates.

A movable lower jaw 29 may be provided to cooperate with larger or double-duty cam element 21a of front axle 13 in such a manner as to alternately open and close said lower jaw 29 against fixed upper jaw 12, simultaneously with the reciprocating movement of front legs 20. To achieve this, end movable jaw 29 is provided with a medial rearward extension or lever 30 pivoted in any suitable manner to base portion 10. Thus, as best shown in Fig. 4, rearward extensions 30 may be formed with an integral bearing lug 31 pivoted by means of a pin 32 between a pair of integral bearing shoulders 33 formed on base portion 10 forwardly of integral boss 18. Lever or extension 30 must be of sufficient length to be intermittently actuated by cam element 21a during the rotation of front axle 13 and front wheels 16. Thus as lever 30 is raised by cam element 21a the lower jaw 29 will move downwardly to open position as shown in broken outline in Fig. 4. In order to tilt lever 30 to close lower jaw 29 after cam element 21a has temporarily passed out of engagement with said lever 30 pending the next successive engagement between said cam element 21 and said lever 30, the free end of said lever 30 is formed with a heavy enlargement 34 serving to counterweight lower jaw 29. The double-duty cam 21a abuts and operates arm 30 while the single-duty cam 21 oscillates the front leg-supporting member 17.

The toy body may be provided with a movable, preferably segmented tail portion 35 comprising a plurality of segments 36. Each segment 36 may be provided with a reduced annular shoulder 37 upon which an adjoining segment 36 may be mounted by means of a respective pivot pin 38. The forward edges 36a of each segment 36 are preferably angularly inclined to allow pivotal motion of segments 36 about their respective pivots 38. The front segment 36 is pivotally secured by means of a respective pivot pin 38 to an annular shoulder 10a which is formed at the rear end of base portion 10. The medial rearward extension 25b, as clearly shown in Figs. 1 and 4, is of sufficient length to project within the front segment 36 of tail portion 35. Thus, as the toy body is drawn along a supporting surface

and leg-supporting member 25 is oscillated by cam elements 24, the free end of extension 25b will alternately thrust against opposite sides of front segment 36 to impart movement to the tail portion 35 in simulation of the "play" or swishing action of the tail of the animal simulated.

The toy body may be drawn along a supporting surface by means of a string S passing through the nose of upper portion 11, as shown in Fig. 2.

Since certain modifications may be made in the toy body of the invention without departing from the scope thereof, it is intended that all matter contained in the foregoing description and shown in the accompanying drawings be interpreted merely as illustrative and not in a limiting sense.

What is claimed is:

1. A toy animal which comprises a body, an axle turnably connected to said body, supporting wheels connected to said axle, a horizontal oscillatory leg-supporting member pivotally connected by a vertical pivot pin to said body forwardly of said axle, said body having a head which has an upper jaw which is fixed to said body, said head having a lower jaw which is fixed to a longitudinal and rearwardly extending arm which is pivoted to said body by a horizontal pivot pin which is located forwardly of said vertical pivot pin, said arm having a weight which normally holds said lower jaw in closed position, said front axle having a pair of cams, said leg-supporting member having rearwardly extending lugs, said cams being shaped and mounted to alternately contact with said lugs to oscillate said leg-supporting member about said vertical pivot pin, one of said cams being a double-duty cam of sufficient length and being shaped and located to also intermittently turn said arm to intermittently move said lower jaw to open position.

2. A toy animal according to claim 1, in which said double-duty cam is shaped and located to abut and turn said arm while said double-duty cam is spaced from the respective lug.

3. A toy animal which comprises a body, an axle turnably mounted in said body, supporting wheels connected to said body, an oscillatory rear leg-supporting member pivoted to said body by a vertical pivot pin rearwardly of said axle, said axle having cam means adapted to oscillate said leg-supporting member, said leg-supporting member having a rearward tail-operating extension, a tail which comprises a plurality of segments, the front segment being hollow and being connected to said body by a vertical pivot pin, each segment after the front segment being connected by a vertical pivot pin to the next forwardly preceding segment, said extension being located in said front segment and being shaped to oscillate said front segment.
